UNITED STATES PATENT OFFICE.

GEORGE ELMER BARNHART, OF DELAND, ILLINOIS.

GATE.

SPECIFICATION forming part of Letters Patent No. 769,784, dated September 13, 1904.

Application filed January 16, 1904. Serial No. 189,349. (No model.)

To all whom it may concern:

Be it known that I, GEORGE ELMER BARNHART, a citizen of the United States, residing at Deland, in the county of Piatt and State of Illinois, have invented a new and useful Gate, 5 of which the following is a specification.

This invention relates to swinging gates; and it has for its object to greatly simplify the construction of the operating mechanism 10 thereof.

One of the objects of the invention is to provide a simple, durable, and efficient operating mechanism for swinging gates which can be controlled from a distance, so that the 15 gate will be capable of being swung open by a person in a vehicle or upon horseback in a convenient manner.

Another object of the invention is to provide a gate-operating mechanism capable of 20 being applied to an ordinary gate without materially altering the construction thereof.

Other objects and advantages of the invention will be specifically described hereinafter, it being understood that changes in form, proportion, and minor details of construction 25 may be made without departing from the spirit or sacrificing any of the advantages of the invention.

In the drawings, Figure 1 represents a perspective view of a gate constructed in accordance with my invention. Fig. 2 is a perspective view of the operating device. Fig. 3 represents a plan view of the gate, showing the gate closed in full lines and partially open in 35 dotted lines. Fig. 4 represents a similar view showing the gate open in full lines and partially open in dotted lines. Fig. 5 represents in side elevation a portion of the gate and its operating mechanism.

The reference-numeral 1 designates the gate-post, to which is hinged the swinging gate 2. The lower hinge 3 may be of any desired construction; but the upper hinge is of a peculiar construction to coöperate with the 40 operating mechanism.

The hinge member carried by the gate consists of a pair of parallel arms 5 and 6, connected by a connecting-bar 7, which is fastened to the gate end in any convenient manner.

The lower arm 5 is pivoted to a right-angled-disposed lip 11 on the end of the vertical hinge member 12 carried by the post, so that the gate will be free to swing in either direction. To the terminal of the upper arm 6 is centrally pivoted a lever 10, disposed on 50 substantially a horizontal plane and connected to the sliding latch-bar 14 of the gate by two flexible connections 15 and 16, both terminally connected to the latch-bar and engaging opposite ends of the lever 10. In order to brace 55 the lever, an integral inclined brace-arm 17 is provided, which projects from one end of the lever and is pivoted to the arm 5 in alignment with the pivot of the lever. This arrangement will sufficiently brace the gate and 60 operating-lever so as to take off all unnecessary strain. When in a state of rest, the lever 10 lies diagonally across the gate-post and the free end or arm thereof extends rearwardly. The ring 19, carried by the end of this arm, 65 is connected to the connection 21, which is attached to the throw-lever 23 on one side of the gate, and the ring 18 on the other end of the lever is attached to the chain 20, which is attached at its other end to the throw-lever 22 70 on the other side of the gate. These levers 22 and 23 are pivoted to the beam 24, supported 75 by the gate-post 1 and the latch-post 25.

Hand operating-cords 26 are carried by the levers 22 and 23, so that a pull upon one of 80 the flexible connections 15 or 16, exerted through the levers and connections 20 or 21, will operate the gate. When the gate is closed, a pull upon either one of the levers will swing the gate toward the latch-post 25, 85 and when the gate is swung open to its full extent the spring-latch 27 will engage a catch 28 on the post 25, so that the gate will remain open until the latch is released. For convenience I have shown cords as depending from 90 the ends of the levers 22 and 23; but other means of imparting movement thereto may be used, if desired.

When the gate is closed, with the operating mechanism arranged as shown in full lines in 95 Fig. 3, a pull on chain 21 will release the latch-bolt 14 and swing the gate a quarter-turn into the position shown in dotted lines in Fig. 3,

when the momentum of the gate will cause it to swing into wide-open position, as shown in full lines in Fig. 4.

The gate being open, as shown in full lines in Fig. 4, to close it a pull is exerted on the chain 20, which will cause the lever 10 to move and release the latch from the catch 28 and swing the gate into dotted-line position, (shown in Fig. 4,) when its momentum will carry it forward into closed position.

I claim as my invention—

1. The combination with a gate-post and a swinging gate carried thereby, of a horizontal intermediately-pivoted lever normally set 15 obliquely to the gate, means connecting the opposite ends of the lever with the gate-latch to release the latter, a brace extending from the lever and pivoted in vertical alinement with the pivot of the lever, and operating de- 20 vices located at opposite sides of the gate and connected to the respective adjacent ends of the lever.

2. The combination with a gate-post and a swinging gate carried thereby, of a horizontal lever loosely fulcrumed at an intermediate 25 point upon the pintle of one of the gate-hinges and normally set obliquely to the gate, means connecting the opposite ends of the lever with the gate-latch to release the latter, 30 and operating devices located at opposite sides of the gate and connected to the respective ends of the lever.

3. The combination with a gate-post and a swinging gate carried thereby, of a horizontal lever intermediately pivoted upon the upper end of the pintle of one of the gate-hinges and normally set obliquely to the gate, a brace extending downwardly from one end of the lever and pivoted to the lower end of the said 40 pintle, means connecting the opposite ends of the lever with the gate-latch to release the latter, and operating devices located at opposite

sides of the gate and connected to the respective adjacent ends of the lever.

4. The combination with a gate-post and a 45 swinging gate, of a stationary hinge member carried by the post, a movable hinge member having spaced upper and lower arms, a pintle piercing the arms and the hinge member on the post, a horizontal lever loosely pivoted at 50 its intermediate point upon the upper end of the pintle and resting upon the upper arm of the movable hinge member, said lever being normally set obliquely to the gate, a brace inclined downwardly and inwardly from the lever with its lower end supported upon the lower arm of the movable hinge member and pierced by the pintle, means connecting the opposite ends of the lever to the gate-latch for releasing the latter, and operating de- 55 vices located at opposite sides of the gate and connected to the respective adjacent ends of the lever.

5. A gate-operating device comprising a stationary hinge member having a perforate ear, 65 a movable hinge member having spaced upper and lower perforate ears, a pintle for engagement with the perforate ears to pivotally connect the hinge members, a horizontal lever having an intermediate opening for the 70 reception of the upper end of the pintle, a brace extending downwardly from the lever and having its lower end provided with a perforation to loosely receive the pintle, latch connections secured to opposite ends of the 75 lever, and operating connections also secured to the opposite ends of the lever.

In testimony that I claim the foregoing as my own I have hereto affixed my signature in the presence of two witnesses.

GEORGE ELMER BARNHART.
